ILLUMINABLE ADVERTISING SIGN

Jerome H. Steinberg, Brooklyn, N. Y.

Application November 14, 1949, Serial No. 6,035

Term of patent 3½ years

(Cl. D1—12)

To all whom it may concern:

Be it known that I, Jerome H. Steinberg, a citizen of the United States of America, residing in Brooklyn, county of Kings, and State of New York, have invented a new, original, and ornamental Design for an Illuminable Advertising Sign, of which the following is a specification, reference being had to the accompanying drawing, forming part thereof.

Figure 1 is a front elevation of an illuminable advertising sign, showing my new design.

Figure 2 is a top plan view of the illuminable advertising sign shown in Figure 1.

Figure 3 is a side view of the illuminable advertising sign.

The back and bottom of the sign are plain and the left hand side is similar to the side shown in Figure 3.

I claim:

The ornamental design for an illuminable advertising sign, as shown and described.

JEROME H. STEINBERG.
